UNITED STATES PATENT OFFICE.

JAMES HORSLEY, OF GLADE MILLS, PENNSYLVANIA, ASSIGNOR OF ONE-HALF TO JOHN B. GREGORY, OF GLADE MILLS, PENNSYLVANIA.

OIL-WELL PUMP.

SPECIFICATION forming part of Letters Patent No. 710,778, dated October 7, 1902.

Application filed January 6, 1902. Serial No. 88,540. (No model.)

To all whom it may concern:

Be it known that I, JAMES HORSLEY, a citizen of the United States, residing at Glade Mills, in the county of Butler and State of Pennsylvania, have invented certain new and useful Improvements in Oil-Well Pumps, of which the following is a specification, reference being had therein to the accompanying drawings, forming part of this specification, 10 in which—

Figure 1 is a partial sectional view of my improved pump inserted in the tubing of a well, the liner-valve barrel being shown in its lowermost position. Fig. 2 is a similar 15 view showing the liner-valve barrel raised to the limit of its upward stroke. Fig. 3 is a partial sectional view, on an enlarged scale, showing the liner-valve barrel lowered, corresponding to Fig. 1. Fig. 4 is a similar view 20 showing the liner-valve barrel raised, corresponding to Fig. 2, the liner-valve or stand-pipe in both Figs. 3 and 4 being shown in elevation. Fig. 5 is a vertical sectional view, on a further enlarged scale, of the upper portions 25 of the liner-valve or stand-pipe, illustrating the construction and arrangement of the packing, packing-rings, and other details, the surrounding liner-valve barrel being also shown in section. Fig. 6 is a view 30 in elevation of the upper sections of the liner-valve barrel, the packing-rings and a portion of the upper packing having been removed. Fig. 7 is a detail perspective view, 35 partially in section, of the upper spring-bearing ring. Fig. 8 is a similar view of one of the interfitting split packing-rings. Fig. 9 is a similar view of the lower fluid-compression ring. Fig. 10 is a sectional view, on a further enlarged scale, showing the lower end 40 of the liner-valve, the liner-valve barrel, and the standing valve mounted in the lower end of the working barrel. Fig. 11 is a similar view 45 showing such parts in the same relative arrangement, the whole construction being shown in section. Fig. 12 is a cross-sectional view, on a further enlarged scale, approximating the full size, taken on the line XII-XII of Fig. 11. Fig. 13 is a similar view on the line XIII-XIII of Fig. 11. Fig. 14 is a 50 similar view on the line XIV-XIV of Fig. 11.

My invention relates to improvements in

oil-well or other fluid pumps, and has for its object the construction of a pump adapted to be located in the tubing and working barrel of the well and to elevate the fluid therethrough by reciprocating movement of a liner-valve barrel with the various details of construction and mode of operation as shall be more fully hereinafter set forth. 55

Referring now to the drawings, 22 represent the tubing of the well, the lower end of which tubing is attached by suitable coupling to the usual working barrel 3, in the lower end of which is located the customary standing valve 4, adapted to permit upward flow of the oil, but to prevent its downward return in the usual manner. 60

A represents a standing pipe or liner-barrel composed of sections of pipe 5, 6, and 7, connected by couplings 8, the lowermost section 70 5 having attached to it and projecting downwardly therefrom a short section 9, terminating in a removable cap 10, preferably secured upon the lower end of the section 9. The cap 10 is provided with a number of perforations 11, through which the oil freely passes upwardly into the interior of the liner-valve upon upward motion of the liner-valve barrel. The section 9 is provided with a plurality of packing-rings 12, tightly engaging 80 around it in position and adapted to fit against the interior of the working barrel 3 and to make therein a fluid-tight fit and to bear with sufficient force to support the liner-barrel in position preferably immediately above the 85 standing valve 4.

The liner-barrel A is provided at its upper end with a standing valve 13, the case of which is screwed upon the top of the upper section 7, as shown, adapted to permit upward travel of fluid and to prevent its return downwardly. The sections 6 and 7 are preferably tapered, as clearly shown in Figs. 5 and 6, so that as these sections are brought close together by adjustment of the couplings 95 pressure will be exerted in a longitudinal direction upon the surrounding divided packing-rings and packing, so as to take up wear and repack these parts.

Surrounding the stationary liner-barrel or stand-pipe is the liner-valve barrel, consisting of a tube or shell 14, adapted to reciprocate

up and down, and between such barrel and the sections 6 and 7 is interposed the packing just referred to. The section 7 is wrapped with any suitable packing substance—as, for 5 instance, wool (indicated at 15) or any other suitable or desirable material—an adjustable thimble 16 being preferably provided immediately underneath the standing valve 13 by which such packing may be compressed, and 10 for the purpose of providing a seat therein the thimble 16 is undercut on a bevel, as indicated at 17. The section 6 is surrounded by a series of split rings 18, (shown in detail in Fig. 8,) the split therein being preferably 15 at an angle, and each of such sections is tapered upon the outside upper portion, as shown at 19, and at the lower inner portion, as shown at 20, so that when a series of such rings are assembled around the section of 20 pipe they will nest into each other and each ring will tend to expand the next adjacent one under longitudinal pressure. The lower packing-ring 21 is preferably solid and rests upon the coupling 8, while the uppermost ring 25 22 (shown in detail in Fig. 7) is also preferably made solid and is hollowed out in the interior, as at 23, for the purpose of receiving packing material 24. As thus assembled the series of split rings, with the terminal solid 30 rings, provides a means for packing the interior of the liner-valve barrel by the exertion thereon of longitudinal pressure. Such pressure is exerted by a stiff coiled spring 25, surrounding the upper end of the section 6 and 35 bearing against the coupling 8 and ring 22. The lower end of the barrel 14 is provided with an annular terminal extension 26, surrounding the section 5, and provided with a series of inner longitudinal ports or passages 40 27, by which upon downward movement of the barrel oil may pass upwardly around the outside of the section 5 and to the interior of a bell-shaped ring 28, (shown more clearly in detail in Fig. 9,) the purpose of which is to 45 permit a limited amount of oil to pass upwardly between it and the section 5 in the space 29 on the downward stroke of the barrel, but which will retard the flow of the oil in the upward stroke of the barrel, and will 50 thus provide through such intervening oil in space 29 and in the space above between section 5 and the liner-valve barrel 14 a back pressure against the packing-rings 18, so as to approximately equalize and counteract the 55 pressure upon them from above. Thus in the downstroke by reason of the inner tapering face 30 of the ring 28 fluid will pass upwardly into the space 29, from which, however, it will not so readily escape in the upward travel of 60 the barrel, but will be compressed therein, thereby thus accomplishing the desired end of providing a counteracting pressure below.

The barrel is provided at its upper portion with a cage 31, carrying a check-valve 32, 65 adapted to open on the downward stroke, permitting oil to flow outwardly from the interior of the barrel to the interior of the

tubing 2, the valve seating itself upon the upward stroke and the volume of oil above the valve being raised during such upward 70 stroke by a connecting or sucker rod or pitman 33, secured, as shown in Fig. 3, to the upper portion of the cage. As thus constructed when the liner-valve barrel has been lowered in the working barrel (the entire 75 structure, including the outer barrel, being lowered by means of the connecting-rod 33) reciprocating motion of the liner-valve barrel 14 will on the upward stroke create a suction 80 in the interior of the liner-barrel A, causing fluid to pass upwardly through the standing 85 valve 4 into the interior of the sections 9, 5, 6, and 7, raising valve 13 and filling the space within the liner-valve barrel above such valve 13 and below the valve 32. Upon the 90 downstroke valves 13 and standing valve 4 will be seated, valve 32 will open and oil will flow outwardly above such valve to the interior of the tubing and be raised therein and discharged therefrom in proportionate quantities 95 at the top of the well upon each subsequent operation of the pump. The construction as I have shown and described it is very efficient in operation, the packing is capable of performing its functions in a highly- 100 satisfactory manner, provision has been made at all points for taking up wear, and the pump has in continuous practice proved to be an efficient device for the purpose.

Changes and variations may be made in 100 the construction, design, proportions, or other details by the skilled mechanic or in its operation in use by others without departing from my invention, and all such changes and variations are to be considered as within the 105 scope of the following claims.

What I claim is—

1. In an oil-well pump, the combination of a stationary tubular stand-pipe provided with means for locating it in a working barrel, surrounding expandable packing-rings, and an upper check-valve; and an outer movable barrel provided with a check-valve at its upper end, a connecting-rod, and means at its lower end, adapted to facilitate circulation to 110 the interior space on the downstroke and to retard circulation therefrom on the upstroke.

2. In an oil-well pump, the combination of a stationary tubular stand-pipe provided with expandable packing-rings adapted to hold it 115 in position in a working barrel; surrounding interfitting expandable rings, and an upper check-valve; and an outer movable barrel provided with a check-valve at its upper end, a connecting-rod and means at its lower end 120 adapted to facilitate circulation to the interior space on the downstroke and to retard circulation therefrom on the upstroke.

3. In an oil-well pump, the combination of a stationary tubular stand-pipe, provided with 130 expandable packing-rings, adapted to hold it in position in a working barrel, surrounding divided interfitting expandable rings, and an upper check-valve; and an outer movable

barrel provided with a check-valve at its upper end, a connecting-rod, and means at its lower end adapted to facilitate circulation to the interior space on the downstroke and to retard circulation therefrom on the upstroke.

4. In an oil-well pump, the combination of a stationary tubular stand-pipe provided with expansible packing-rings adapted to hold it in position in a working barrel, surrounding divided tapered interfitting expansible rings, and an upper check-valve; and an outer movable barrel provided with a check-valve at its upper end, a connecting-rod, and means at its lower end adapted to facilitate circulation to the interior space on the downstroke and to retard circulation therefrom on the upstroke.

5. In an oil-well pump, the combination of a working barrel provided with a standing valve at its lower end, a stationary tubular stand-pipe provided with expansible packing-rings adapted to hold it in position within the working barrel, packing devices surrounding said standing pipe at its upper portion, and a check-valve at its upper end; and an outer movable barrel provided with an upper check-valve, a connecting-rod attached thereto, circulation-ports at the lower end of said movable barrel permitting a flow of fluid to the interior thereof, and an inner tapered ring above said circulation-ports adapted to facilitate circulation to the interior space on the downstroke and to retard circulation therefrom on the upstroke.

35 6. In an oil-well pump, the combination of a working barrel, a standing valve therein, a stationary tubular stand-pipe provided at its lower portion with expansible packing-rings adapted to hold it in the interior of the working barrel, packing material surrounding the upper portion of the stand-pipe, a series of interfitting spring packing-rings surrounding the middle portion, and an upper check-valve; and an outer movable barrel provided with an upper check-valve, a connecting-rod, and means at its lower end adapted to facilitate circulation to the interior space on the downstroke and to retard circulation therefrom on the upstroke.

50 7. In an oil-well pump, a stationary tubular stand-pipe composed of a plurality of sections, packing material surrounding one of the sections, a series of tapered interfitting split spring packing-rings surrounding another of the sections, a compressing-spring adapted to exert pressure upon one end of said packing-rings, an upper check-valve, and expansible packing-rings adapted to hold the stand-pipe in the interior of a working barrel.

60 8. In an oil-well pump, a stationary tubular stand-pipe composed of a plurality of tapered sections, packing material surrounding one of

the sections, a series of interfitting spring packing-rings surrounding another of the sections, an upper check-valve, and expansible 65 packing-rings adapted to hold the stand-pipe in the interior of a working barrel.

9. In a pump, a stand-pipe having one or more tapered sections, and a series of surrounding split spring packing-rings, the endmost of such rings being hollowed out and provided with packing material, and a coiled spring surrounding the stand-pipe, and bearing against said endmost ring.

10. In a pump, a stand-pipe having one or more tapered sections and a series of surrounding split interfitting tapered spring packing-rings, the endmost of such rings being hollowed out and provided with packing material, and a coiled spring surrounding the 75 stand-pipe, and bearing against said endmost ring.

11. In a pump, a stand-pipe composed of one or more tapered sections and a series of surrounding interfitting spring packing-rings 85 bearing directly thereon with means for compressing the rings longitudinally.

12. In a pump, a stand-pipe composed of one or more tapered sections, a series of surrounding interfitting spring packing-rings 90 bearing directly thereon, terminal solid rings, and a spring adapted to exert pressure on the packing-rings.

13. In a pump, a stand-pipe composed of one or more tapered sections, a series of surrounding interfitting spring packing-rings, a terminal ring providing an end bearing, a similar ring providing a bearing at the opposite end provided with internal packing and a spring adapted to exert pressure on the 95 packing-rings.

14. In a pump, a stand-pipe composed of one or more tapered sections, a series of surrounding interfitting tapered divided spring packing-rings bearing directly thereon, terminal rings, and a spring adapted to exert pressure on the 100 packing-rings.

15. In a pump, a liner-valve barrel adapted to telescopically inclose a stand-pipe provided with an upper check-valve, said liner-valve 110 barrel having a lower surrounding terminal extension provided with a series of inner longitudinal ports, and an internal bell-shaped ring above said ports adapted to facilitate circulation to the interior space on the downstroke and to retard circulation therefrom on the upstroke.

In testimony whereof I affix my signature in presence of two witnesses.

JAMES HORSLEY.
